N. E. RICE,
LOCK FOR MOTOR VEHICLES.
APPLICATION FILED JUNE 18, 1920.

Patented Oct. 3, 1922.

2 SHEETS—SHEET 2.

INVENTOR:
NORMAN E. RICE,
BY Cheever & Cox

ATTYS.

UNITED STATES PATENT OFFICE.

NORMAN E. RICE, OF CHICAGO, ILLINOIS.

LOCK FOR MOTOR VEHICLES.

Application filed June 18, 1920. Serial No. 389,831.

To all whom it may concern:

Be it known that I, NORMAN E. RICE, a citizen of the United States, residing at Chicago, in the county of Cook and State 5 of Illinois, have invented a certain new and useful Improvement in Locks for Motor Vehicles, of which the following is a specification.

My invention relates to locks, and while 10 it is applicable to a variety of uses, it is especially useful as a lock for automobiles. In its developed form, shown in the accompanying drawings, the lock forms a control for the electric ignition circuit and also 15 a lock for preventing the rotation of the steering post in the steering column.

The object of my invention is to provide an efficient, non pickable lock serving either or both of these functions. In the illustrated embodiment of the invention the parts 20 are controlled by a rotary element or "rotor" which when in normal or "running" position enables the vehicle to be operated, and in another position prevents it from being 25 operated. The rotor is urged away from normal or running position by a spring, and one of the contributory objects of my invention is to provide supplemental means for insuring the holding of the rotor in 30 running position and prevent its being released as a result of the vibration of the vehicle. This supplemental means is, according to the present design, controlled by a separate or supplemental key.

35 I accomplish my objects by the mechanism illustrated in the accompanying drawings in which—

Figure 1 is an assembly view of the lock, the parts being shown chiefly in axial section,

Figure 2 is a transverse section on the line 2—2, Figure 1,

Figure 3 is an end view looking towards the right in Figure 1, a portion of the casting being broken away to better reveal the construction,

Figure 4 is a transverse sectional view on the line 4—4, Figure 1,

Figure 5 is a transverse sectional view on 50 the line 5—5, Figure 1,

Figure 6 is a sectional view on the line 6—6, Figure 4,

Figure 7 is a sectional view on the line 7—7, Figure 1, and

Figure 8 is a side view of the plunger 55 whose function is to lock the steering post against rotation.

Like numerals denote like parts throughout the several views.

In the form selected to illustrate the invention the lock has a casing 1 which is preferably formed in two halves riveted or otherwise rigidly secured together. At one end it has a clamp for securing it to the steering column 2 of the vehicle. This plate 65 is here shown to consist of an integral concave portion 3 and a cap 4 which is riveted or otherwise rigidly secured to it. The main body of the casing is approximately cylindrical and is closed at the outer 70 end by a rotary plate 6 which is held in position by a flanged ring 8. Fastened to this plate is a rotor which has a base 10 riveted or otherwise rigidly fastened to the inside of the plate. By preference this rotor is 75 formed in two halves riveted or otherwise held together. It has a key hole 12 which extends longitudinally for receiving the main key 14. A helical spring 16 is fastened at one end to a lug 17 carried by the 80 casing at the inner end, as shown at the right in Figure 1. The other end of the spring is fastened to the rotor as at the point 18. The parts are so arranged that the tension of the spring tends to rotate the rotor 85 in a clockwise direction when viewed as in Figures 2 to 5.

In this particular embodiment of the invention a finger 20, preferably of insulating material, is fastened to the rotor in such 90 manner that it will when the rotor is in normal position (corresponding to running conditions of the vehicle) engage a contact finger 22 and hold it in engagement with a stationary contact 23. The parts 22 and 23 95 form a switch for controlling the ignition circuit of the vehicle. It will be sufficient for the present purpose to say that the ignition circuit includes two conductors 24, 26 which are secured to the parts 22 and 23 100 respectively and are enclosed in insulation 27 and pass out through a conduit 28 leading from the side of the casing. It will be understood that there is a switch of this character for each igniter, for example, if 105 four spark plugs are employed four switches will be employed, as illustrated in Figure 1. When the rotor is in normal or run-

ning position, shown in Figure 2, the control switches 22, 23 will be held closed and when the rotor moves away from this running position and releases the movable contactors 5 22 the switches automatically open thus opening the ignition circuits and preventing the charges in the combustion cylinders from being ignited; consequently the vehicle cannot be driven unless the rotor is in 10 running position.

The rotor is held in running position by a tumbler or pawl 32 pivotally mounted in a bracket 34 located within the casing as shown in Figure 2. This pawl is adapted to engage a lug 36 formed on the rotor. The pawl extends across the key hole and the key is so formed that when it is inserted in the key hole it will lift the tumbler and release the rotor and permit the spring to rotate the finger 20 out of engagement with the switch contact 22, thus opening the ignition circuit. When the rotor is in normal running position and the key is inserted, the serrated upper edge of the key will pass between two stationary wards or barriers 38 whose lower edge is serrated or irregularly formed to prevent rotary movement of the rotor in case any but the correctly formed key is inserted. A second pair of stationary wards or barriers 40 is also provided, and adjacent to one of them is fastened a ward plate 42 which has an extension 43 adapted to form a stop for the lug 44 formed on the rotor. This stop arr- rests the rotor in the non running position illustrated in Figure 4. In the present design the non running position is approximately 330° from the running position of the rotor, although this, of course, is largely a matter of design.

As previously mentioned, my device is capable not only of controlling the ignition circuit, but also locking the steering post against angular movement. I will now describe the parts more intimately associated with this characteristic of the invention:

Arranged longitudinally within the rotor, concentrically therewith, is a squared socket 46 adapted to slidingly receive the squared shank 48 of a plunger 49 shown in position in Figure 1 and separately in Figure 8. The inner end 50 of this plunger or locking bar is adapted to enter a recess 52 formed in the side of the steering post

52 formed in the side of the steering post
54. Said end 50 is flaringly tapered or
dovetailed, and the recess 52 is correspond-
ingly undercut to receive it. The result is
that if the plunger is in acting position
within the recess an attempt on the part of
60 the operator to rotate the steering post will
tend simply to make the engagement cor-
respondingly tighter. This effectually pre-
vents the danger of the plunger becoming
rounded off at the inner end thus enabling
65 it to be forced back under a cam-like action

in case pressure is exerted on the steering wheel in an angular direction. A helical compression spring 56 encircles the plunger. One end of the spring abuts a shoulder 57 formed within the rotor and the other end abuts a collar 58 fastened to the plunger by means of a set screw 59 or otherwise. The collar has a projection 60 at its inner end adapted to enter a recess 62 formed behind a shoulder 63 as best shown in Figures 1 and 7. This recess is formed in a boss 64 formed on the inner side of the inner end of the casing, and the result is that when the rotor is rotated to non running position, the projection or nose 60 will enter the recess 62 behind the shoulder 63 and the result will be two-fold: first, the plunger is permitted to shift longitudinally and insert the flaring head 50 into the recess 52, and second, the shoulder will arrest the rotor against further movement by the main spring 16. It will thus be observed that I have provided two devices for limiting the movement of the rotor under the action of the spring, to wit, the stop 43 and the shoulder 63. It will be understood, of course, that one of these two stops may be dispensed with if desired.

The projection 60 is beveled at the back, thus producing a cam, and the parts are so constructed that when the rotor is subsequently rotated by the key from non running to running position, the cam will automatically force the plunger toward the left, Figure 1, and thus retract the end 50 from the recess 52 and release the steering post. 95 100

I have provided means for locking the rotor in non running position. These means include a dog 68 best shown in Figures 4 and 6. This dog is pivotally supported on a stationary bracket 67 and is backed up by a spring 70. When the key has been inserted and the tumbler 32 raised the spring 16 rotates the rotor and brings it to the position shown in Figure 4, as previously explained. So long as the key remains in place it holds the dog 68 non acting, as illustrated in Figure 4; but as soon as the key is withdrawn it permits the dog to drop behind the lug 36 and prevent the rotor from being rotated back again to running position. Thus the rotor is adapted to be locked in non running position as well as to be locked in running position. 105 110 115

It is desirable not to have to rely upon the key for rotating the rotor against the force of the main spring 16. I have therefore provided a separate handle 72 which is fastened to the plate 6 of the rotor, as shown at the left end of Figures 1 and 3. 125

In some cases it may be desired to provide double insurance against the rotating of the rotor from non running to running position. For this purpose I have provided a supplemental key 76 shown at the right 130

end of Figure 1 and also in Figure 5. This is adapted to be inserted through a slot 78 in the inner end of the casing 1 and to lift a tumbler 80 pivoted upon the stationary bracket 82. This tumbler is backed up by a spring 83 and therefore tends to drop behind a fin 84 formed near the right end of the rotor (see Figures 1 and 6). When this supplemental locking device is employed it is necessary as a prerequisite to rotating the rotor from running to non running position to insert the key 76 and lift the tumbler 80 as well as inserting the main key 14 and lifting the tumbler 32.

The operation of the device will now be readily understood. Let it be assumed that the parts are in running position shown in Figure 2. The fingers 20 which are of insulating material, hold the switch contacts 22 in engagement with the switch contacts 23, thus putting the ignition circuits on closed circuit (although subject to the operation of the distributor or whatever type of timing mechanism may be employed). The projection 60 on the collar 58 is in contact with the inner end of the boss 64 and thus holds the plunger 48 retracted in opposition to the force of its spring 56. Thus the steering post is free to rotate. If, now, it is desired to put the vehicle in such condition that it cannot be driven away, that is, if it is desired to convert the vehicle to non running condition, the operator inserts the supplemental key 76 thus lifting the tumbler 80 and causing it to free the fin 84 on the rotor. This key may be simply left in position. The operator then inserts the main key 14, thus lifting the tumbler 32 and permitting the main spring 16 to rotate the rotor from running position, shown in Figure 2, to non running position, shown in Figure 4. This causes the fingers 20 to leave the movable switch contacts 22 thus putting the ignition system on open circuit. It also causes the collar 58 to be rotated so far that its projection 60 will drop into the recess 62 formed in the boss 64. This permits the dovetailed end of the plunger 48 to enter the under cut recess 52 in the steering post and hold the latter locked against rotation. With the ignition circuits open and the steering post locked, the vehicle, of course, cannot be operated. The withdrawing of the main key 14 permits the dog 68 to drop behind the lug 44 and hold the rotor locked in non running position. When the operator wishes to again render the vehicle operative, he inserts the main key 14, thus lifting the dog 68, and enabling him to rotate the rotor back to running position, shown in Figure 2. This restoring of the rotor to running position against the force of the spring 16 is aided by using the handle 72. The operator still grasping the handle 72, next withdraws the main key 14, thus per-

mitting the tumbler 32 to drop behind the lug 36 and hold the rotor locked. He then withdraws the supplemental key 76 and thus permits the tumbler 80 to drop into engagement with the fin 84 and thus supplement 70 the action of the dog 32 in holding the rotor in running position.

While I have shown and described the rotor as controlling both the ignition circuit and the steering post, it is evident that either 75 the control switches or the steering post lock may be omitted without impairing the efficiency of the portion which is retained. It will also be understood that while I have described the conductors 24, 26 as employed 80 for the conduction of current for the ignition where the vehicle is furnished with an internal combustion engine, these conductors may, with analogous result, represent the main motor conductors of an electrically 85 driven vehicle.

It will be noted that the switch contacts are so formed as to move directly toward and from each other, thus producing a jump spark when contact is broken. This produces a surging on the line which is of value in keeping the points of the spark free from soot and carbon.

Having thus described my invention, what I claim as new and desire to secure by Letters Patent, is:

1. A lock having a casing, a rotor within the casing, a spring tending to rotate the rotor from unlocking to locking position, a tumbler for holding the rotor in unlocking 100 position, and a key insertible into the casing for lifting the tumbler, the rotor having a slot for the reception of the key and the casing having a stationary ward adapted to lie on one side of the key when the latter is 105 within the rotor for preventing the key from rotating unless it is properly configurated.

2. A lock having a locking element, a casing, a rotor therein adapted to control the locking element, a key insertible into the 110 casing and rotor, a spring for urging the rotor from unlocking to locking position, a tumbler for holding the rotor in unlocking position, the tumbler being adapted to be lifted by the insertion of the key, a stop for 115 limiting the rotation of the rotor under the influence of the spring, and a dog adapted to drop behind the rotor for holding it in locking position, said dog being held non-acting by the presence of the key in the rotor. 120

3. A lock having a locking element a casing, a rotor therein, adapted to control the locking element, a key insertible into the casing and rotor eccentrically to the rotor, a spring for urging the rotor from unlocking 125 to locking position, a tumbler for holding the rotor in locking position, the tumbler being adapted to be lifted by the insertion of the key, a stop for limiting the movement of the rotor under the action of the spring, 130

- and a handle fastened to the rotor and accessible from the exterior of the lock for assisting to rotate the rotor against the force of its spring.
5. A lock having a locking element a casing, a rotor therein adapted to control the locking element, a key insertible into the casing and rotor eccentrically to the rotor, a spring for urging the rotor from unlocking 10 to locking position, a tumbler for holding the rotor in locking position, the tumbler being adapted to be lifted by the insertion of the key, a stop for limiting the movement of the rotor under the action of the spring,
- 15 a dog adapted to engage the rotor and hold it in locking position, said dog being adapted to be lifted by the key, and a ward lying at the side of the key when the rotor is in locking position for limiting the rotation of the 20 rotor.
5. A lock having a locking element a casing, a rotor therein adapted to control the locking element, a key insertible into the casing and rotor, a spring for urging the 25 rotor from unlocking to locking position, a tumbler for holding the rotor in unlocking

position, said tumbler being adapted to be lifted by the insertion of the key, a dog for holding the rotor in locking position, said dog being adapted to be lifted by the insertion of the key, and stationary wards, one located adjacent to the key when the rotor is in unlocking position and the other located adjacent to the key when the rotor is in locking position. 30

6. A lock having a locking element a casing, a rotor therein adapted to control the locking element, a spring for urging the rotor from unlocking to locking position, a tumbler adapted to hold the rotor in unlocking position, said tumbler being adapted to be lifted by the insertion of the key, a second tumbler adapted to engage the rotor and hold the latter in unlocking position, and a supplementary key insertible into the casing 40 from the opposite end thereof and adapted to lift the second tumbler to permit the rotor to rotate under the action of the spring. 45

In witness whereof, I have hereunto subscribed my name.

NORMAN E. RICE.
